CLAIM

The ornamental design for a gasket for an electric plug, as shown and described.

DESCRIPTION

FIG. 1 is a perspective view of a gasket for an electric plug of our new design;

FIG. 2 is a front elevational view thereof, a rear elevational view being a mirror image;

FIG. 3 is a left side elevational view thereof, a right side elevational view being a mirror image; and,

FIG. 4 is a top plan view thereof, a bottom plan view being a mirror image.

The broken lines shown represent unclaimed subject matter and form no part of the claimed design.
